PAGE 2

FIG. 2

FIG. 3

FIG. 4

FIG. 7

FIG. 5

FIG. 6

FIG. 1 is a perspective view of the combination service station and car wash embodying the new design;

FIG. 2 is top plan view thereof;

FIG. 3 is a front elevation thereof less canopy;

FIG. 4 is a right side elevation thereof;

FIG. 5 is a left side elevation thereof;

FIG. 6 is a rear elevation view thereof; and

FIG. 7 is a front elevation view of the canopy forming part of the combination service station and car wash embodying the new design.

We claim:

The ornamental design for a combination service station and car wash, as shown and described.
